UNITED STATES PATENT OFFICE

112,090

DESIGN FOR A TOY PROJECTOR GUN

Earl Rundles, Cincinnati, Ohio

Application September 7, 1938, Serial No. 79,762

Term of patent 3½ years

To all whom it may concern:

Be it known that I, Earl Rundles, a citizen of the United States, residing at Cincinnati, in the county of Hamilton and State of Ohio, have invented a new, original, and ornamental Design for a Toy Projector Gun, of which the following is a specification, reference being had to the accompanying drawing, forming part thereof, in which:

Fig. 1 is a rear perspective view of a toy projector gun, showing my new design;

Fig. 2 is a top plan view; and

Fig. 3 is a side elevational view of the same.

I claim:

The ornamental design for a toy projector gun, substantially as shown.

EARL RUNDLES.
